(57) **CLAIM**

The ornamental design for a model vehicle nerf bar as shown and described.

DESCRIPTION

FIG. 1 is an upper, right, front perspective view of a model vehicle nerf bar showing our new design;

FIG. 2 is an upper, left, rear perspective view thereof;

FIG. 3 is a lower, right, rear perspective view thereof;

FIG. 4 is a lower, left, front perspective view thereof;

FIG. 5 is a front elevation view thereof;

FIG. 6 is a rear elevation view thereof;

FIG. 7 is a right-side elevation view thereof;

FIG. 8 is a left-side elevation view thereof;

FIG. 9 is an upper plan view thereof; and,

FIG. 10 is a lower plan view of the model vehicle nerf bar. In the drawings, the broken lines illustrate portions of the model vehicle nerf bar that form no part of the claimed design.
